CAN OPENER SUPPORT

Walter W. Edlund, Burlington, Vt., assignor to
Edlund Company, Burlington, Vt., a partnership

Original application August 22, 1945, Serial No.
611,996. Divided and this application August
13, 1946, Serial No. 690,203

2 Claims. (Cl. 248—295)

1

My present invention relates to can openers and has for its object to provide an instrument in which the mechanism for severing the top of the can is contained in a head which is mounted on a vertically movable part adjustable relatively to a base on which the cans are supported, provision being made for fixing the post in any one of a variety of positions for operating on cans of different sizes when a large number of such are to be opened successively.

Another object of my invention is to provide, in an instrument having the above described characterization, means which allow the supporting post a movement within limits in its otherwise fixed position for the accommodation of cans of a selected size to accommodate cans within the tolerances or variations allowed the manufacturers, as well as to allow for such movement as may be required to permit the heads of cans to be placed in operative position beneath the top severing mechanism to facilitate the rapid handling of cans of specific sizes.

This application is a division of the original application filed by me August 22, 1945, S. N. 611,996.

To these and other ends my invention comprises further improvements and advantages as will be further described in the accompanying specification, the novel features thereof being set forth in the appended claims.

In the drawings:

Figure 1 is a side elevation showing a can opener embodying my invention.

Figure 2 is a vertical sectional cross section of the head carrying the can top severing knife and its operating mechanism.

Figure 3 is a bottom plan view of the base plate on which the vertically movable post is adjustably supported.

Figure 4 is a detail view partly in section showing the retaining pin used for locking the post at a given height which is used when a large number of cans of standard size are to be operated upon.

Figure 5 is a detail partly in section of the locking device used for securing the supporting post in any selected position of adjustment, preliminary to fixing the post by means of the pin shown in Fig. 4.

Figure 6 is a cross sectional view of the supporting post or column taken on the line 6x—6x of Fig. 1.

Similar reference numerals, in the several figures, indicate similar parts.

A can opener embodying the instant invention 55 shown particularly in Fig. 5. This means of se-

2

comprises in part a head 1 carrying the can top puncturing and severing element. This head is mounted on the upper end of a post or column 2 composed of a rectangular channel, as shown 5 in Fig. 6, which is guided in a sleeve 4 depending at one end of a base plate 5 adapted to be secured to a table top or other horizontal support to form a platform on which cans to be opened are placed in an upright position against the forward edge 10 of the column or post 2. Cans thus supported are in position to be engaged by the head 1 when it is moved downwardly as a result of guiding the post 2 in the sleeve 4.

The can top severing mechanism is carried 15 within the head 1 and comprises a knife blade 6 which is adapted to be moved downwardly on an inclined guide 7 by means of a yoke 8, the bifurcated end of which lies in an annular groove in a collar 9. The collar 9 is capable of being reciprocated on a shaft 10, against the tension of a spring 11, by an operating handle 12 pivoted on the upper end of the shaft and having a cam surface 13 bearing against the collar 9. The arrangement of these parts is such that when the handle is elevated in the position shown in Fig. 2, the knife 6 is retracted, and when the handle is rotated into a horizontal position, (Fig. 1) the knife will be caused to penetrate the top of the can. Secured to the lower end of shaft 10 is a knurled wheel 14 with which the bead on the upper edge of a can is held in contact by the action of the knife 6 in puncturing the can top. Rotation of the handle 12 thus causes rotation of a can and the complete severance of its top.

The socket 4 of the base plate in which the post 2 is guided is cast with a rectangular opening, the sides of which are recessed so that it is only necessary to machine the corners to provide a smooth running guide for the post 2. Inasmuch as the latter is made in channel form of sheet metal it is desirable therefore to provide a novel means of clamping it in its adjusted position so as to avoid distorting the post. This I accomplish by placing the clamping screw 15 which is used for preliminary clamping purposes at an angle of 45° on one of the outer corners of the socket 4, as shown in Figs. 1 and 3. Also in order to obviate the possibility of marring the corner of the post or column I form the inner end 40 of the screw with a separate tip piece 16 which does not rotate when in frictional engagement with the corner of the post. This tip has a stud 45 extending into a recess in the screw bearing at its inner end against a steel ball bearing 17, as shown particularly in Fig. 5. This means of se-

curing the post to hold the head 1 in adjusted position is to be used when successively operating on cans of miscellaneous sizes and also when initially setting the apparatus for successively operating on a number of cans all of the same size. It is usual in restaurants and institutional kitchens and the like to operate upon a large number of cans of a given size at one time, hence I provide a second locking means for the post which may be thrown into and out of action as desired.

Cans for preserved fruit, vegetables and the like are furnished by the can manufacturers in standard sizes and to accommodate those most frequently used I provide in one of the sides of the channel forming the post 2, a series of spaced recesses which may be in the form of notches or apertures properly positioned according to can sizes with respect to the head 1, as shown by 18 in dotted lines in Fig. 1. Thus several apertures cooperate with a locking stud 19 mounted on one side of the socket 4 and movable inwardly and outwardly thereon. This stud is shown in detail in Fig. 4. It is slideable in a cylindrical boss 20 and at its outer end is provided with a finger gripping knob 21. Intermediate its ends are spaced annular channels 22 and 23 between which is an annular arcuate surface 24. A radial passage in the boss 20 carries a pin 25 the inner end of which engages in one or the other of the aforementioned channels, whereby the stud is held in either its operative or inoperative position, and may be easily changed from one position to the other by moving it longitudinally. In order to yieldingly hold the pin 25 in its recess and urge it inwardly I provide a surrounding split circular spring band 26 which lies within an annular channel 27 on the boss 20.

An especial object is accomplished by the association of the various parts above described in that with the cutter 6 retracted and a can placed on the supporting platform or base 5, the post or column 2 may be lowered until the projecting edge of the head 1 rests upon the top edge or bead of the can and is permanently secured by locking the post on its support. It will be seen that this placing of the can occurs wholly in a horizontal direction. Consequently after the top has been severed and the cutter retracted the removal of the can is likewise in a horizontal plane so that there need be no spilling of its contents.

When it is desired to remove the head from a single can, or a multiplicity of cans, the initial position of the severing instrument, with reference to the platform 5, is determined by the height of a selected can by lowering the severing head into engagement therewith, whereupon the post is first secured by the wing nut 15. If thereafter it is determined that a number of cans of the size for which the adjustment has already been made are to be operated upon the stud 19 will be moved inwardly into engagement with one of the apertures 18 and the nut 15 released. This mode of operation is provided because it is found in practice that certain vari-

ations occur in cans of a given size, hence by making the apertures 18 elongated, the post 2 may be elevated slightly as required to accommodate an over-size can without disturbing the general adjustment of the instrument. It has also been found in practice that when the position of the cutting head has been once determined for operation on cans of a given size it is not expedient to allow the post to be elevated any considerable distance when operating on successive cans. This is because of the carelessness of operators and the loss of time experienced if the adjustment is accidentally altered. Hence such movement is limited by the length of the apertures 18 which are only slightly in excess of the tolerance variations that are considered permissible in the manufacture of cans.

What I claim as my invention and desire to protect by Letters Patent is:

1. The combination with a support for can bodies, having a rectangular guide sleeve, a rectangular channel forming a post guided in the sleeve and a set screw on a corner of the guide cooperating with a corner of the post for initially securing it with its upper end in selected position relative to the can support, said post having a series of oblong recesses spaced from its upper end with reference to the lengths of cans of different sizes, of a push pull stud on the guide sleeve adjustable into engagement with one or another of said recesses following the initial selected fixation of the post by said set screw and serving to maintain the post in such selected position when the set screw is released.
2. The combination with a support for can bodies having a guide sleeve, a post vertically adjustable in the sleeve, means on the sleeve engaging the post for securing the upper end of the post in selected position relative to the can support, said post being provided with a series of recesses located in spaced relation to its upper end with reference to the length of standard sized cans, said recesses having a length in excess of allowable variations in the length of said cans, of a locking pin on the sleeve cooperating with a selected one of the said recesses following the initial selected fixation of the post.
